CLAIM

The ornamental design for a sport bottle rack dispensing system, as shown and described.

DESCRIPTION

FIG. 1 is a perspective view of an ornamental design for a sport bottle rack dispensing system according to the present invention, in which dashed broken lines define unclaimed features;

FIG. 2 is a front view thereof;

FIG. 3 is a side view thereof;

FIG. 4 is a top view thereof;

FIG. 5 is a bottom view thereof;

FIG. 6 is a perspective view of an ornamental design of another embodiment of a sport bottle rack dispensing system according to the present invention, in which dashed broken lines define unclaimed features;

FIG. 7 is a perspective view of an ornamental design of another embodiment of a sport bottle rack dispensing system according to the present invention, in which dashed broken lines define unclaimed features;

FIG. 8 is a perspective view of an ornamental design of another embodiment of a sport bottle rack dispensing system according to the present invention, in which dashed broken lines define unclaimed features;

FIG. 9 is a perspective view of a plate of an embodiment of the sport bottle rack dispensing system according to the present invention;

FIG. 10 is a perspective view of a clip of an embodiment of the sport bottle rack dispensing system according to the present invention;

FIG. 11 is a front view of the clip of FIG. 10; and,

FIG. 12 is a side view of the clip of FIG. 11.

The plate and clip in FIGS. 9-12 are shown separately for clarity of illustration. The difference in the alternate embodiments shown in FIGS. 6-8 is the addition of extra clips.
